UNITED STATES PATENT OFFICE.

GEORG KIRKEGAARD, OF NEW YORK, N. Y., ASSIGNOR TO IMPERIAL STOPPER COMPANY, A CORPORATION OF MAINE.

BOTTLE-STOPPER.

No. 897,542.

Specification of Letters Patent.

Patented Sept. 1, 1908.

Application filed July 24, 1907. Serial No. 385,236.

To all whom it may concern:

Be it known that I, GEORG KIRKEGAARD, a citizen of the United States, and a resident of the city of New York, in the county of New York and State of New York, United States of America, have invented certain new and useful Improvements in Bottle-Stoppers, of which the following is a specification.

My invention relates to a bottle stopper or cap which may be attached to and locked upon a bottle or similar structure to seal such a structure, and its object is to provide a simple and efficient construction for such a device.

I will describe my invention in the following specification and point out the novel features thereof in claims.

Referring to the drawings, Figure 1 represents, in sectional side elevation, the upper portion of a bottle with one of my improved stoppers attached thereto. Fig. 2 is a plan view, partly in section, on an enlarged scale, of one of my bottle stoppers, and Fig. 3 is a side elevation, partly in section, of the same stopper. Fig. 4 is a sectional plan view of a portion of the flange of one of my stoppers showing the form of one of its folds before it is put onto a bottle.

Like characters of reference designate corresponding parts in all of the figures.

10 designates a bottle, the upper portion of which is provided with an annular bead which forms a shoulder 11, about or directly below the opening or mouth of the bottle to 35 which the stopper is to be attached.

20 designates a cap, preferably of metal such as commercial tin-plate, and comprises a circular disk 21 having an annular depending straight flange 22. The inner diameter 40 of this flange is slightly greater than the outside diameter of the bead about the mouth of the bottle. A packing 23 of cork or other resilient material is placed within the flange and against the inner surface of the disk 21.

45 At points about the periphery of the flange 22 the lower portion of the flange is pinched or folded together to form projecting shoulders as shown at 24. This causes the lower edge of the flange to be drawn inward as 50 shown at 25 so that its diameter is less than that of the straight sides of the flange.

The cap is first constructed with a straight flange with fluted portions as shown at 26 in Fig. 4. The cap is first pressed down upon 55 the mouth of the bottle, jar or other structure

to which it is applied, which structure may be filled with desired material. The packing 23 is thus compressed between the mouth of the bottle and the top of the cap to effect a tight closure of the bottle, and the sides of 60 the flange surround the bead on the bottle neck. The flange is of sufficient depth to extend down over the shoulder 11 formed by the bead. While thus held under pressure over the mouth of the bottle the lower portion 65 of the flange, at the fluted portions about its periphery, is folded together in the manner shown at 24 in Fig. 2. This has a double effect; in the first place, it draws the straight sides of the flange tightly about the 70 bead of the bottle, thus increasing its sealing effect, and in the second place, it causes the lower edge or rim 25 of the flange to be drawn in under the bead of the bottle neck and thus securely locks the cap onto the bottle. At the same time it forms upon the outer surface of the flange a plurality of projecting shoulders, parallel with the axis of the bottle, of double the thickness of the metal of the flange. These shoulders materially stiffen the cap and add to its strength. 75

To remove the cap from a bottle it is only necessary to pry it off at the flange. This will cause the folded portions 24 to be spread apart until the diameter of the lower edge or 80 rim of the flange is sufficiently large to allow it to slip over the bead and off from the bottle.

What I claim is:—

In combination with a bottle having a neck 90 with an annular circumferential bead, a bottle stopper comprising a circular disk having an annular depending flange, said flange being provided with an inwardly projecting rim at its lower edge adapted to extend beneath 95 said bead, whereby the vertical section of the flange is sharply curved or bent, a packing of resilient material within said flange, and a plurality of symmetrically spaced-apart folds in the flange, forming a plurality of strengthening shoulders, said folds following the curved or bent contour corresponding to said vertical section of the flange. 100

In testimony whereof I have signed my name to this specification in the presence of 105 two subscribing witnesses.

GEORG KIRKEGAARD.
